VEHICLE CHAIR

Alfred C. Hoven and Willard H. Bond, Jr., Grand
Rapids, Mich., assignors to American Seating
Company, Grand Rapids, Mich., a corporation
of New Jersey

Application May 1, 1948, Serial No. 24,488

8 Claims. (Cl. 155—195)

1

The present invention relates to chairs and more particularly to chairs of the type installed in passenger vehicles, and especially adaptable for installation in motorbusses of the intra-city transit type.

The primary objects of the invention are to provide a vehicle chair in which the seat and back are formed of molded plastic; to provide a chair frame fabricated of metal tubing, on which the molded plastic seat and back may be quickly assembled; and in general to provide such a vehicle chair which is comfortable for the occupant, free from squeaks and rattles, attractive in appearance, and reasonably economical in manufacture.

One embodiment of the invention is illustrated by the accompanying drawings, wherein:

Figure 1 is a front elevational view of a chair especially adapted for installation in a motor bus of the intracity transit type;

Figure 2 is a fragmentary, horizontal sectional view of the same, taken on line 2—2 of Figure 1;

Figure 3 is an enlarged, vertical sectional view of the same, taken on line 3—3 of Figure 1;

Figure 4 is a greatly enlarged fragmentary vertical sectional view of certain parts of the chair, taken on line 4—4 of Figure 2; and

Figure 5 is a similarly enlarged fragmentary vertical sectional view of certain other parts of the chair, taken on line 5—5 of Figure 2.

Referring now in detail to those drawings, wherein like parts are designated by the same numerals in the several views, the chair there shown is mounted on a chair support which comprises spaced upstanding pedestals 10 having horizontal bottom flanges 11 adapted to be secured to the floor of a motorbus as by means of bolts 12. The upper end of each pedestal 10 slopes rearwardly-downwardly and is provided with inwardly extending lugs 13 the purpose of which is made apparent hereinafter.

The chair frame is preferably fabricated from a continuous length of metal tubing which is bent to form a substantially horizontal front rail 14, side rails 15 extending rearwardly from the opposite ends of said front rail and thence angularly upwardly, and a top rail 16 commonly known as a "grab rail" connecting the upper ends of the upstanding portions of the side rails 15. The front rail 14 of the frame constitutes a seat supporting bar for the forward edge of the chair seat. A back supporting rail or bar 17 is provided for supporting the upper edge of the chair back, said bar 17 comprising a straight length of metal tubing having its opposite ends

2

secured as by welding to the side rails 15 of the frame slightly below the "grab rail" 16 and generally parallel thereto. An intermediate supporting bar or rail 18 of channel bar formation extends transversely of the frame rearwardly of the bar 14 and below the bar 17, said channel bar 18 having its opposite ends secured as by welding to the side rails 15 of the frame at the angles formed between the rearwardly and the upwardly extending portions of said side rails 15, and the channel of said channel bar 18 opening in an upwardly and forwardly direction.

Spaced channel bars 19 extend forwardly-rearwardly of the frame between the front rail 14 and the intermediate rail 18, and these channel bars 19 have their opposite ends in abutment with and secured as by welding to the rails 14 and 18 thus completing the chair frame. The chair frame is mounted on the chair support or pedestals 10 by means of bolts 20 passing through aligned apertures in the channel bars 19 and the lugs 13 of pedestals 10 and provided with nuts 21 on the lower ends thereof. It will be seen that the chair frame thus provides a substantially horizontal seat supporting portion and a substantially vertical back supporting portion.

The chair seat 22 and the chair back 23 are preferably separately formed of rigid molded plastic and are shaped to conform generally to the body forms of two chair occupants, the chair shown being of the two-passenger variety. The chair seat 22 has its forward edge 24 curled downwardly to engage the seat supporting rail or bar 14, and may be secured to said bar 14 as by means of screws 25 extending upwardly through apertures 26 in the bar 14 and threaded in lugs 27 which are molded in the seat 22 and which rest on the chair frame. Additional lugs 28 similar in form to the lugs 27 may be provided at the sides of the seat's underside for supporting the seat proper spacedly above the side rails 15 of the chair frame. The rearward edge of the chair seat 22 is provided with a rearwardly-downwardly extending flange 29 seated in the forward part of the channel in the transverse channel bar 18.

The molded plastic chair back 23 has its upper edge 30 curled rearwardly to engage the back supporting bar 17, and the opposite sides of the back 23 are provided with rearwardly extending fins 31 which rest against the upwardly extending portions of the side rails 15 of the frame. The lower edge of the chair back 23 has a rearwardly-downwardly extending flange 32 seated in the rearward part of the channel in the transverse channel bar 18.

Fastening means comprising bolts 33 are passed through aligned apertures in the side walls of the channel bar 18 and in the flanges 29 and 32 of the chair seat and chair back respectively, and nuts 34 are provided for the threaded lower ends of the bolts 33.

In assembling the seat 22 and back 23 to the chair frame, the back's flange 32 is seated in the channel bar 18 and the back's curled upper edge 30 is simultaneously hooked over the back supporting bar 17 of the frame. The seat's flange 29 is next seated in the channel bar 18 and the seat's curled forward edge 24 is simultaneously made to engage the seat supporting bar 14 of the frame. The chair is thus assembled, and the flanges 29 and 32 fill the channel in the channel bar 18 so that each opposes removal of the other. The screws 25 are then set in place thus preventing accidental or unauthorized removal of either the seat 22 or the back 23 from the structure. The parts are additionally secured in assembly by placement of the bolts 33 and nuts 34, which bolts and nuts also effectively prevent any rattles or squeaks which might otherwise occur by reason of slight relative movements of the parts. When so assembled the chair seat and chair back provide a smooth continuous curved surface generally conforming to the seat and back contour of the seated human body, as best illustrated in Figure 3.

It will thus be seen that a vehicle chair has been provided which is quiet in use, convenient in assembly, reasonably economical in manufacture and comfortable for the occupants thereof, and while but one specific embodiment of the invention has been herein shown and described it will be understood that the construction shown may be modified without departing from the spirit and scope of the invention as defined by the following claims.

We claim:

1. In a chair structure of the class described: a chair support; a chair frame mounted on the chair support and comprising a substantially horizontal seat supporting bar, a substantially horizontal back supporting bar spaced rearwardly from and above said seat supporting bar, and a substantially horizontal intermediate supporting bar spaced rearwardly from said seat supporting bar and below said back supporting bar, said intermediate bar being of upwardly-forwardly opening channel formation; a chair seat having its forward edge mounted on the seat supporting bar and having its rearward edge provided with a rearwardly-downwardly extending flange seated in the forward part of the channel in the intermediate bar; and a chair back having its upper edge mounted on the back supporting bar and having its lower edge provided with a rearwardly-downwardly extending flange seated in the rearward part of the channel in the intermediate bar; said chair seat and said chair back each comprising a unitary sheet of rigid material so formed that when secured together the seat and back provide a smooth continuous curved surface generally conforming to the seat and back contour of the seated human body.

2. In a chair structure of the class described: a chair support; a chair frame mounted on the chair support and comprising a substantially horizontal seat supporting bar, a substantially horizontal back supporting bar spaced rearwardly from and above said seat supporting bar, and a substantially horizontal intermediate supporting bar spaced rearwardly from said seat supporting

bar and below said back supporting bar, said intermediate bar being of upwardly-forwardly opening channel formation; a chair seat having its forward edge mounted on the seat supporting bar and having its rearward edge provided with a rearwardly-downwardly extending flange seated in the forward part of the channel in the intermediate bar; a chair back having its upper edge mounted on the back supporting bar and having its lower edge provided with a rearwardly-downwardly extending flange seated in the rearward part of the channel in the intermediate bar; and fastening means passing through the side walls of the channelled intermediate bar and through the seat and back flanges seated within said channel; said chair seat and said chair back each comprising a unitary sheet of rigid material so formed that when secured together the seat and back provide a smooth continuous curved surface generally conforming to the seat and back contour of the seated human body.

3. In a chair structure of the class described: a chair support; a chair frame mounted on the chair support and having a substantially horizontal seat supporting portion and a substantially vertical back supporting portion; a substantially horizontal channel bar secured to the frame transversely thereof at the junction of the frame's seat supporting and back supporting portions, and with the channel thereof opening in an upwardly-forwardly direction; a chair seat having its forward part supported by the seat supporting portion of the frame and having its rearward edge provided with a flange seated in the forward part of the channel in said channel bar; and a chair back having its upper part supported by the back supporting portion of the frame and having its lower edge provided with a flange seated in the rearward part of the channel in said channel bar; said chair seat and said chair back each comprising a unitary sheet of rigid material so formed that when secured together the seat and back provide a smooth continuous curved surface generally conforming to the seat and back contour of the seated human body.

4. In a chair structure of the class described: a chair support; a chair frame mounted on the chair support and having a substantially horizontal seat supporting portion and a substantially vertical back supporting portion; a substantially horizontal channel bar secured to the frame transversely thereof at the junction of the frame's seat supporting and back supporting portions, and with the channel thereof opening in an upwardly-forwardly direction; a chair seat having its forward part supported by the seat supporting portion of the frame and having its rearward edge provided with a flange seated in the forward part of the channel in said channel bar; and a chair back having its upper part supported by the back supporting portion of the frame and having its lower edge provided with a flange seated in the rearward part of the channel in said channel bar, said seat and back flanges substantially filling the channel in said channel bar so that each opposes removal of the other; said chair seat and said chair back each comprising a unitary sheet of rigid material so formed that when secured together the seat and back provide a smooth continuous curved surface generally conforming to the seat and back contour of the seated human body.

5. In a chair structure of the class described: a chair support; a chair frame mounted on the chair support and having a substantially hori-

zontal seat supporting portion and a substantially vertical back supporting portion; a substantially horizontal channel bar secured to the frame transversely thereof at the junction of the frame's seat supporting and back supporting portions, and with the channel thereof opening in an upwardly-forwardly direction; a chair seat having its forward part supported by the seat supporting portion of the frame and having its rearward edge provided with a flange seated in the forward part of the channel in said channel bar; a chair back having its upper part supported by the back supporting portion of the frame and having its lower edge provided with a flange seated in the rearward part of the channel in said channel bar, said seat and back flanges substantially filling the channel in said channel bar so that each opposes removal of the other; and additional fastening means passing through the side walls of the channel bar and through the seat and back flanges seated within said channel; said chair seat and said chair back each comprising a unitary sheet of rigid material so formed that when secured together the seat and back provide a smooth continuous curved surface generally conforming to the seat and back contour of the seated human body.

6. In a chair structure of the class described: a chair support; a chair frame mounted on the chair support and comprising a continuous length of metal tubing bent to form a front rail, side rails extending rearwardly from the opposite ends of said front rail and thence angularly upwardly, and a top rail connecting the upper ends of the upstanding portions of said side rails; a substantially horizontal back supporting rail having its opposite ends secured to the side rails of the frame near the top rail; a channel bar having its opposite ends connected to said side rails at the angles formed between the rearwardly and the upwardly extending portions thereof, said channel bar having the channel therein opening in an upwardly direction; a chair seat having its forward edge secured to the front rail of the frame and having its rearward edge provided with a downwardly extending flange seated in the forward part of the channel in said channel bar; and a chair back having its upper edge secured to said back supporting rail and having its lower edge provided with a downwardly extending flange seated in the rearward part of the channel in said channel bar; said chair seat and said chair back each comprising a unitary sheet of rigid material so formed that when secured together the seat and back provide a smooth continuous curved surface generally conforming to the seat and back contour of the seated human body.

7. In a chair structure of the class described: a chair support; a chair frame mounted on the chair support and comprising a continuous length of metal tubing bent to form a front rail, side rails extending rearwardly from the opposite ends of said front rail and thence angularly upwardly, and a top rail connecting the upper ends of the upstanding portions of said side rails; a substantially horizontal back supporting rail having its opposite ends secured to the side rails of the frame near the top rail; a channel bar having its opposite ends connected to said side rails at the angles formed between the rearwardly and the upwardly

upwardly extending portions thereof, said channel bar having the channel therein opening in an upwardly direction; a chair seat having its forward edge secured to the front rail of the frame and having its rearward edge provided with a downwardly extending flange seated in the forward part of the channel in said channel bar; a chair back having its upper edge secured to said back supporting rail and having its lower edge provided with a downwardly extending flange seated in the rearward part of the channel in said channel bar; and fastening means passing through the side walls of the channel bar and through the seat and back flanges seated within said channel; said chair seat and said chair back each comprising a unitary sheet of rigid material so formed that when secured together the seat and back provide a smooth continuous curved surface generally conforming to the seat and back contour of the seated human body.

8. In a chair structure of the class described: a chair support; a chair frame mounted on the chair support and comprising a substantially horizontal seat supporting bar, a substantially horizontal back supporting bar spaced rearwardly from and above said seat supporting bar, and a substantially horizontal intermediate supporting bar spaced rearwardly from said seat supporting bar and below said back supporting bar, said intermediate bar being of upwardly-forwardly opening channel formation; a plastic chair seat molded to form a downwardly curled forward edge engaging the seat supporting bar and a rearwardly-downwardly extending flange on its rearward edge seated in the forward part of the channel in the intermediate bar; and a plastic chair back molded to form a rearwardly curled upper edge engaging the back supporting bar and a rearwardly-downwardly extending flange on its lower edge seated in the rearward part of the channel in the intermediate bar; said chair seat and said chair back being so formed that when secured together they provide a smooth continuous curved surface generally conforming to the seat and back contour of the seated human body.
